REPRODUCTION APPARATUS

BACKGROUND OF THE INVENTION

In an electrostatic copying machine of the type using a photoconductive layer for developing a latent electrostatic image of the document to be copied and thereafter developing and transferring the image to a copy sheet, various processing stations are utilized for uniformly charging, exposing and developing the photo-sensitive surface, transferring the developed image to a copy sheet, fusing the transferred image on the copy sheet, cleaning the photoreceptive surface, etc. Provision must also be made for the efficient and accurate movement of sheets of copy paper from the supply station to the transfer station of the machine.

With the increasing amount of paper work that must be accomplished in various industries in recent years, commercial automatic copier/reproduction machines have been developed to provide extremely high speed copying of original documents. As machine speeds increase, the damage or jams that could occur in a machine in the event of a malfunction also increases. To minimize the possibility of damage, a number of sensors are employed in the machine to monitor the various machine functions and the paper position throughout its path in the machine. In the event of a malfunction, the sensors, acting through the machine control system, will cause the machine to shut down.

In a high speed xerographic copier of the type employing a photoreceptor belt, a number of images may be disposed on the belt before the sheet of paper adapted to receive the foremost image is fed from the paper supply station. In the event of a malfunction of the paper feeder, these electrostatic images would proceed through the developer and the transfer rollers to the cleaning station of the machine wherein the belt is ordinarily cleaned prior to the charging thereof and exposure of a new image. If the paper is not present at the transfer station when the developed image arrives thereat, the xerographic surface with the toner image thereon can cause numerous problems. Toner may be transferred from the belt to the transfer rollers. The toner that is not transferred to the transfer roll will be conveyed by movement of the belt to the cleaning station of the machine. Since the cleaning station is designed to remove the residual toner remaining after the majority of the toner is transferred to the copy sheet, in the event that a copy sheet is not present at the transfer rolls, excess quantities of toner will reach the cleaning station, putting an undue load thereon. Besides the problems presented at the transfer station and the cleaning station, this type of operation is extremely wasteful of xerographic toner.

SUMMARY OF THE INVENTION

This invention relates to a method for minimizing problems in a xerographic machine caused by the misfeed of copy paper therethrough by discharging the electrostatic image on the photoconductive surface before that portion of the surface reaches the developer station, de-energizing the developer, and removing the electrical bias on the transfer rolls to prevent transfer of toner thereto and minimize the possibility of carrying excess toner to the cleaning station of the machine.

BRIEF DESCRIPTION OF THE DRAWINGS

FIG. 1 is a schematic sectional view of a reproduction machine showing the various processing stations therein; and,

FIG. 2 is a schematic block diagram of the control system to provide a programmed shutdown of the machine in the event of a paper misfeed.

DESCRIPTION OF THE PREFERRED EMBODIMENT

For a general understanding of an electrostatic processing system in which the invention may be incorporated, reference is had to FIG. 1 in which various components of a system are schematically illustrated. As in most electrostatic systems such as a xerographic machine, a light image of the original to be reproduced is projected onto the sensitized surface of a xerographic plate to form an electrostatic latent image thereon. Thereafter, the latent image is developed with an oppositely charged developing material comprising carrier beads and smaller powder particles triboelectrically adhering thereto to form a xerographic powder image corresponding to the latent image on the plate surface. The powder image is then electrostatically transferred to a support surface to which it may be fixed by a fusing device whereby the powder image is caused permanently to adhere to the support surface.

The electrostatically attractive developing material commonly used in electrostatic reproduction systems comprises a pigmented resinous powder hereinafter referred to as "toner", and "carrier" of larger granular beads formed from a material removed in the triboelectric series from the toner so that a triboelectric charge is generated between the toner powder and the granular carrier. The carrier also provides mechanical control so that the toner can be readily handled and brought into contact with the exposed xerographic surface where the toner is attracted to the electrostatic latent image from the carrier to produce a visible powder image on the xerographic surface.

In the illustrated machine, an original D to be copied is placed upon a transparent support platen P, fixedly arranged in an illumination assembly generally indicated by the reference numeral 10. While upon the platen, an illumination system L comprising two or more lamps and reflectors is flash energized to direct light rays upon the original to produce image rays corresponding to the informational areas on the original. The image rays are projected by means of an optical system 11 to an exposure station A for exposing the photosensitive surface of a moving xerographic plate in the form of a flexible photoconductive belt 12. In moving in the direction indicated by the arrow, prior to reaching the exposure station A, that portion of the belt being exposed would have been uniformly charged by a corona device 13 indicated at a belt run extending between belt supporting rollers 14 and 15, the latter being the drive roller for the belt. The exposure station extends between the roller 14 and a third support roller 16. The belt run between these rollers is encompassed entirely by the exposure station for minimizing the space required by the belt and its supporting rollers.

The exposure of the belt to the light image discharges the photoconductive layer in the areas struck by light whereby there remains on the belt a latent electrostatic image in image configuration corresponding to the light

image projected from the original document. A discharge device, preferably a fluorescent lamp 17 is provided adjacent support roller 16 for reasons to be explained hereinafter.

As the belt surface continues its movement, the electrostatic image passes around the roller 16 to a developer station B located at a third run of the belt in which there is positioned developing apparatus generally indicated by the reference numeral 18. The developer apparatus 18 comprises a plurality of brushes adapted for rotation by a suitable motor 19 to carry developer along the adjacent surface of the upwardly moving inclined photoconductive belt 12 to provide development of the electrostatic image.

The developed electrostatic image is transported by the belt 12 to a transfer station C located at a point of tangency on the belt around the drive roller 15 whereat a sheet of copy paper is moved at a speed in synchronism with the moving belt in order to accomplish transfer of a properly registered developed image. A transfer roller 20 is provided at transfer station C for contacting the upper surface of the copy paper to assure good contact between the copy paper and the belt 12 during transfer of the toner image from the belt to the paper. An electrical bias may be provided on roller 20 to attract the toner from belt 12 to the copy paper.

There is also provided a copy sheet supplying apparatus comprising a main paper feed supply 21 and an auxiliary paper feed supply 22. Each of the paper supplies is adapted to separate sheets from their respective supply stacks and to transport the sheets to a sheet registration station and eventually into contact with the developed image on the belt as the same is carried around the drive roller 15. Control means 23 are operatively associated with each of the paper supply mechanisms 21, 22 and the flash illumination device L for producing an electrostatic latent image on the belt 12 to present a developed image at the transfer station C in timed sequence with the arrival of a sheet of paper, and is coordinated with the activation of other processing and control devices at the precise time that these elements are to function for their intended purpose. A paper sensing device 24 is positioned adjacent the paper path between the paper supply mechanism 21 and 22 and the transfer station C, to determine if the paper is fed therefrom at the proper time relative to the image on the photoreceptor belt.

After the developed image is transferred to a sheet of paper, it is stripped from the belt 12 and conveyed by conveying system 25 into a fuser apparatus generally indicated by reference numeral 26 wherein the developed and transferred xerographic powder image on the sheet material is affixed thereto. After fusing, the finished copy is discharged from the apparatus by a conveyor 27 at a suitable point for collection externally of the apparatus. The toner particles remaining as residue on the developed image and those particles not otherwise transferred are carried by the belt 12 to a cleaning apparatus 28 positioned on the run of the belt between the rollers 14 and 15 adjacent the charging device 13. The cleaning apparatus comprises a discharge device 29 for neutralizing charges remaining on the particles and a rotating brush 30 which operates in conjunction with a vacuum system to remove the residual toner particles from the brush.

As stated heretofore, in a high speed copier of the type illustrated, a number of images may have been

flashed on the belt by the time the sheet of paper is fed for transfer of the foremost image thereto. In the event of a malfunction in the paper feed mechanism which would be sensed by the sensor 24, a number of operations are immediately instituted to avoid deleterious effects on the machine caused by developed images reaching the transfer station in the absence of copy paper thereat. Therefore, upon the sensing of a paper misfeed by sensor 24 the control system 23 is adapted to immediately energize lamp 17, deactivate the developer motor 19, remove the electrical bias on transfer roller 20 and move the transfer roller out of contact with the belt by a suitable mechanism (not shown).

Thus in the event of a paper misfeed, the electrostatic image on the belt passing beneath lamp 17 will be discharged, those images that are passed the lamp when the misfeed is detected and have not reached the developer will not be developed and those images that are developed when the misfeed is detected will not be transferred to the transfer roll since the electrical bias thereon is removed and the roll is withdrawn from the belt. Therefore the cleaning station will only be required to remove toner from one or two developed images rather than all the images that were on the belt prior to the detection of the misfeed.

While we have described the preferred embodiment of our invention it is to be understood that the invention is not limited thereto but may be otherwise embodied within the scope of the following claims.

30. What is claimed is:

1. In a reproduction machine adapted for making copies of an original through a plurality of process steps including exposure of the original to form a latent electrostatic image of the original on a photoconductive surface, developing the image to provide a toner image of the original on the photoconductive surface, providing an electrical bias on the copy paper and holding the copy paper against the toner image by means of an electrically biased transfer roller to transfer the toner image to the copy paper, a method to minimize toner consumption and toner contamination of the machine comprising the steps of:

continuously energizing the transfer roller and maintaining the transfer roller in contact with the photoconductive surface during a normal copy run; removing the electrical bias on the transfer roller moving the transfer roller away from the photoconductive surface in the event of a paper misfeed to prevent transfer of toner to the roller; and, de-energizing the developer to prevent development of latent electrostatic images passing by the developer subsequent to a paper misfeed.

2. A method to minimize toner consumption and toner contamination of a reproduction machine according to claim 1 further including a step of discharging the latent electrostatic images on the photoconductive surface before the imaged areas reach the developer to prevent development thereof in the event of a paper misfeed.

3. In a reproduction machine adapted for making copies of an original through a plurality of process steps including exposure of the original to form a latent electrostatic image of the original on a photoconductive surface, developing the image to provide a toner image of the original on the photoconductive surface, and holding the copy paper against the toner image by suitable holding means adapted for continuous contact

with the photoconductive surface during normal machine operation to transfer the toner image to the copy paper, a method to minimize toner consumption and toner contamination of the machine comprising the steps of:

moving the holding means away from the photoconductive surface in the event of a paper misfeed to prevent transfer of toner thereto and discharging latent image areas on the photoconductive surface in the event of a paper misfeed to prevent development thereof.

4. A method to minimize toner consumption and toner contamination of the machine according to claim 3 further including the step of preventing development of the imaged areas that are not discharged by de- 15 energizing the developer.

5. In a reproduction machine adapted for making copies of an original through a plurality of process steps including exposure of the original to form a latent electrostatic image of the original on a photoconductive surface, developing the image to provide a toner image of the original on the photoconductive surface, and transferring the toner image to a copy paper, a method to minimize toner consumption and toner contamina- 20

5

tion of the machine comprising the steps of; discharging a portion of the latent imaged areas on the photoconductive surface in the event of a paper misfeed and preventing development of undischarged imaged areas on the photoconductive surface by de-energizing the developer.

6. A method for automatically producing copies of an original comprising the steps of; providing an electrostatic charge pattern of the original on a photoconductive surface; developing the charge pattern with an electrically attractive powder as the charge pattern on the photoconductive surface passes a developer station to provide a powder image on the photoconductive surface in conformity with the original; supplying sheets of copy paper to the photoconductive surface in synchronism with the developed image thereon for contact with the image to transfer the powder image to the copy paper; and, discharging the electrostatic charge pattern in the event of a paper misfeed to prevent development of the charge pattern as the photoconductive surface moves past the developer station.
